PROSTHETIC FOOT FOR INJURED OR
SHORT LEGS

Mario Capella Valenti, Barcelona, Spain

Application January 17, 1946, Serial No. 641,729
In Spain February 7, 1945

7 Claims. (Cl. 3—6)

1

My invention consists of a prosthetic or artificial foot which may be applied to injured or short legs. It may be also applied to patients who have a marked shortness of a leg with a more or less important deformity in their foot. By my apparatus they are able in both cases to walk normally.

One of the objects of my invention is to obtain a prosthetic foot than can easily be applied to the injured who have lost one or both feet. This prosthetic foot, once applied, would allow them to make the movements that are made in normal walking, so permitting them to walk nearly as well as before the injury.

Another object of my invention is the possibility of applying this prosthetic foot to patients who have a marked shortness of one leg, so that these patients may also walk without suffering from the difference in the length of their legs.

With these objects in view, my invention consists of a prosthetic or artificial foot formed of different parts which are conveniently articulated and combined by a special mechanism, so that, when walking, the movements made are those made by a normal foot. If the prosthetic foot is applied to an injured person it is set, by an articulation, on a framing or rigid part, constituting an artificial shin portion which is fastened in a convenient way to the portion of the leg that has been left to the injured person. This framing has to be made specially in every case in order to get the form and size required to be applied to this part of the leg. If the prosthetic foot is intended for a person who has one of his legs much shorter than the other, or whose foot or leg is deformed, then the prosthetic foot is articulated to a framing which can be perfectly adapted to the short foot or leg. This framing has in every case the form and disposition required in order that the patient's foot may maintain any convenient position.

The prosthetic foot itself, according to my invention is hollow and made of metal or any other convenient material and it is divided in two different parts; the front part, corresponding to the toe cap, is articulated with the heel part, which is larger, by means of a hinge-joint which is fitted with an elastic device that gives it the necessary mobility during the various stages of walking.

Inside the heel part of the prosthetic foot is the mechanism which brings about the movement to the whole of the prosthetic foot. This mechanism consists of: a cylinder which contains two elastic springs, between which is placed

2

the piston which reciprocates at the interior of the cylinder; a double shock absorber or two shock absorbers which work jointly in such a way that in one of the directions they exert a slight resistance or controlling action and in the other direction they exert a stronger resistance or more accentuated controlling or braking action.

If the prosthetic foot of my invention is applied to a patient who suffers from a marked shortness of one leg, the cylinder, together with its piston and the operating rod, is placed between the axle at the ends of the levers of the shock absorbers and the framing fastened to the leg or passive part of the apparatus. The upper part of the cylinder is articulated with this framing, and the free end of the piston rod is articulated with the axle of the levers of the shock absorbers. The shock absorbers are solidly fixed on the sole in the inside of the heel of the prosthetic foot. The cylinder serves as a connection between the framing and the prosthetic foot. Apart from this joint there is another articulation between the framing and a support solidly attached to the inside of the heel part of the prosthetic foot, which support is placed in front of the two shock absorbers.

In the passive part of the apparatus or framing there are some pieces, of leather for instance, which surround the leg and the front part of the foot, held by means of shoe laces which are fastened with appropriate clasps and eyelets.

In the case of total injury of the foot, the framing, fixing support or passive part of the apparatus consists of a rigid body that surrounds what remains of the leg of the injured person and to this framing is coupled the prosthetic foot. In this case the prosthetic foot may remain completely closed and its articulation or coupling with the framing, or passive part of the same, is done on both sides of the prosthetic leg, these articulations being at the level of the ankle of the opposite normal foot. The upper part of the cylinder is then joined by means of a special articulated device to a piece solidly fastened at the rear wall of the support that contains the stump of the injured leg.

The mechanism may also be inverted and the axle of the shock absorbers be fixed to the framing fastened to the leg, articulating the cylinder to a point of the sole of the prosthetic foot.

In both the case of marked shortness and of total injury of the foot, everything that represents the sole section in the prosthetic foot is coated with a soft material (caoutchouc, felt,

pressed cork, etc.) for the purpose of smoothing the shock against the ground and provide, at the same time, noiseless operation of the apparatus.

In the drawings are shown various forms of construction of the prosthetic foot of my invention.

Figure 1 is a side view, partly in section, of the prosthetic foot coupled to the framing that is fastened to what remains of the leg in the case of total injury of the foot.

Figure 2 is a side view, partly in section, of the lower part of the foot in Figure 1, seen from the opposite side.

Figure 3 is a longitudinal section of the lower part of the foot showing its mechanism.

Figure 4 is a longitudinal section of a prosthetic foot showing a modification specially designed to be applied in some cases of injury, and, finally,

Figure 5 is a side view of the support that is fastened to the patient's leg in the case of shortness of one leg in order to fit on the foot shown in Figures 2 and 3.

As shown in Figures 1, 2, 3 and 4, that is, for cases of injury, my invention comprises a prosthetic foot composed of two parts, the toe part 1 and the heel part 2, coupled together by means of a hinge-joint 3 and an elastic device 4, such as, for instance, a spring.

Inside the heel part 2 of the prosthetic foot there is attached a piece 5, the upper part of which is articulated to the framing 6 which is fastened to the leg of the injured foot, which articulation 7 may consist of, for instance, a ball bearing, and is at the same level as the ankle of the normal foot.

At both sides and somewhat behind the piece 5 there is placed the shock absorber 8, solidly fixed on the sole and in the heel part 2 of the prosthetic foot. The levers 10 and 11 of this shock absorber are coupled to an axle 12, which at its central part is articulated to the rod 13 that carries the piston 14 of the cylinder 15.

The upper end of this cylinder 15 is articulated with a piece 16, solidly fixed to the rear wall of the framing 6 that surrounds the injured leg. The piston 14 of the pump is set between two springs 17 and 18 placed inside the cylinder, there being various means to regulate the tension of the lower spring 18 or of the upper spring 17 independently.

Figure 4 shows a modification in the construction of the prosthetic foot of my invention which differs from the example described before because the cylinder 15, coupled to the shock absorber 8, instead of being disposed in a vertical direction, is disposed in a more or less horizontal position along the sole of the foot.

The operation of this specially constructed prosthetic foot is exactly the same as the one described and shown in Figures 1 to 3, but the disposition of the cylinder in horizontal direction on the sole of the foot diminishes the height of the mechanism, so that the foot may be quite closed on the upper part and it can be more easily used. This modification of the prosthetic foot is suitable in cases in which injury only affects the foot below the ankle.

In this form of construction shown in Figure 4 the shock absorber 8, instead of being fixed to the sole of the foot is mounted on the principal axle 21 of articulation and this axle is joined to the support or rigid part which is fastened to the patient's leg by means of supporting pieces 28 fixed to a bridge or transverse piece 29. The cylinder 15 is placed in a more or less horizontal position inside the foot and upon the sole of the

same and its end is articulated to a piece 26 fixed to the sole of the foot.

The shock absorbing mechanism 8, 9 may take any suitable construction and may consist of one single shock absorber or of two shock absorbers mounted on the same axle. This shock absorbing mechanism is disposed in such a way that, when, in walking, the foot executes the movement of taking the weight on the toe end and lowers the heel part, the shock absorber exerts much resistance, but when the heel part of the foot rises because it rests upon the heel, the shock absorber exerts a much weaker resistance or braking action.

If the prosthetic foot is to be applied to a shortened leg and foot, the shape of the framing will be such as to permit the surrounding of the shortened leg and foot and to keep the latter in a convenient position. With this object in view, 20 the said framing is constituted by rigid parts 19 (Figure 5) articulated together, which are fastened on the shortened leg 20 and foot 21 by means of flexible pieces 22 which are closed by means of shoe laces, clasps and eyelets.

In the rigid pieces 19, parts have been provided 23 and 24, which are attached, respectively, to the cylinder 15 and to the base and lateral walls of the rear inner segment of the prosthetic foot in this case of shortness.

After the foregoing statements it may be realized that those details in the construction of the apparatus which have no influence on its essence are susceptible of variation. As a consequence it may be constructed in any size with the material 35 or materials deemed convenient, being applicable for a shortness of the lower extremity or to replace the injured foot. It is also possible to make use of any type of shock absorber existing in the market, as well as to use the methods deemed 40 more adequate for joining together the different pieces of the apparatus.

I claim:

1. A prosthetic foot for injured or short legs comprising a heel part that forms the body or 45 principal part of the foot and a forward part which forms the end and which is pivotally connected to the heel part by means of a hinge-joint articulation in combination with a spring, said heel part being pivotally connected to a framing 50 which is attached to the patient's leg, and said heel part comprising in its interior a shock absorbing mechanism whose lever is articulated to the end of the rod of a piston sliding in the inside of a cylinder of a spring pump, in order to smooth 55 the movement of the foot upon its point of articulation with the framing fastened to the leg.

2. A prosthetic foot as claimed in claim 1, comprising a support fixed upon the interior part of the sole of the foot, said support holding the axle 60 of the shock absorbing mechanism, another axle parallel to the axle of said shock absorber and pivotally connecting the heel part of the foot to the framing fastened to the patient's leg, a spring pump consisting of a cylinder provided with a piston actuated by springs, said piston sliding in the interior of the said cylinder, the rod of said piston being pivotally connected to the end of the lever of the shock absorber while the free end of the cylinder is pivotally connected to the framing fastened to the patient's leg.

3. A prosthetic foot as claimed in claim 1, comprising a framing or fixing piece fastened to the patient's leg, a support mounted on this piece, a horizontal axle mounted on this support, and forming the rotating axle of the shock absorber,

a spring pump composed of an exterior cylinder inside which reciprocates a piston actuated by springs, the end of the piston rod being pivotally connected to the arm of the shock absorber and the free end of the cylinder being pivotally connected to a support which is fixed to the sole or inside part of the foot.

4. A prosthetic foot as claimed in claim 1, which comprises a hinge-joint connection between the two parts which form the foot in combination with a spring that engages support pieces fixed on the two parts of the foot tending to keep these two parts of the foot in the most open position.

5. A prosthetic foot as claimed in claim 1, in which the two parts, toe end and heel part of the prosthetic foot are coupled by means of a hinge-joint subjected to the action of a spring, a shock absorbing mechanism having been fixed on the bottom and in the interior of the heel part of the prosthetic foot.

6. A prosthetic foot as claimed in claim 1, which comprises a spring pump formed by a cylinder inside which reciprocates a piston; two springs located in the interior of the cylinder, and bearing by one of their ends upon the op-

posite sides of the piston and by the other end upon the two opposite ends of the cylinder, and a rod fixed to this piston that protrudes from the cylinder and is pivotally connected to the arm of the shock absorber.

7. A prosthetic foot as claimed in claim 1, which comprises a framing or fixing piece that is fastened to the leg and foot of the patient in the case of a short leg, said fixing piece being composed of two parts connected by a hinge-joint; a lower part, which corresponds to the toe end of the patient's foot, and which is fixed to the heel part of the prosthetic foot, in front of the shock absorbing mechanism, and an upper part that corresponds to the leg and sole of the patient's foot and is pivotally connected to the top of the spring pump.
